UNITED STATES PATENT OFFICE.

WILLIAM E. GOOD, OF READING, PENNSYLVANIA.

REVERSING APPARATUS FOR STEAM-ENGINES.

SPECIFICATION forming part of Letters Patent No. 253,199, dated February 7, 1882.

Application filed November 21, 1881. (No model.)

To all whom it may concern:

Be it known that I, WILLIAM E. GOOD, of the city of Reading, county of Berks, State of Pennsylvania, have invented a new and useful Improvement in Reversing Apparatus for Locomotive and other Engines, of which the following is a specification.

This improvement relates to that class of locomotive, stationary, and other steam-engines which are provided with a valve-gear adapted to move the same in a forward or backward direction, and is intended to give relief to the engineer and positiveness to the movement of the reversing-lever.

15 The drawing herewith is a general elevation, sectional in part, representing my improvement, in which—

15 A represents a steam-cylinder; A', a cataract-cylinder filled with air, oil, water, or other suitable material, or its equivalent, the purpose of which is to control the movement of the piston B' and, under suitable conditions, to arrest the movement of the same.

20 B and B' are pistons connected together by the piston-rods C C', and with the arm D at D' by a mortise, C².

25 Steam is delivered to the cylinder A by the oscillating valve E or its equivalent, the valve-seat of which is provided with two induction 30 and one exhaust port.

35 The cylinder A' is provided with two passages, a² and a³, leading from opposite ends of the cylinder to the valve-box, which is provided with an oscillating valve, E', or its equivalent. The valves E E' are connected by arms on their spindles to the valve-rod E². This rod is operated by the lever F, being connected thereto at F', the opposite end, F², being connected to the arm D by a link, D². Intermediate 40 between F' and F², at such point as will give the desired movement to the valve-rod C C', I attach a link, G, by a pin, F³, to the lever F, said link being also connected to a lever, H, or its equivalent, of the engine. At the point 45 D' of the arm D provision is made for a free yet positive movement of the arm D between the ends of the mortise C² in the rod C C'.

50 h h', in dotted lines, indicate the forward and backward movement of the lever H or its equivalent, while d d' indicate by dotted lines a corresponding movement of the arm D.

When the lever H is moved toward h a movement will be communicated through the link G to the lever F, thence through the valve-rod E² to the valve E, by which movement 55 steam-pressure is admitted into the cylinder A by the port a, and will drive the piston B toward b' simultaneously with the movement of the valve E. By the direct connection of the rod E² therewith there will be a corresponding movement of the valve E', by which communication will be opened between the ends of the cylinder A' by the ports a² and a³, thus permitting the contents of the cylinder A' to pass with a limited velocity from one end of the cylinder to the other. The movement of the pistons B and B', attached to the arm D by means of the rods C C' and mortise C², will continue so long as steam under pressure is admitted by the valve E into the cylinder A through the 70 port a, and until the motion of the lever H is arrested. When the said lever H is arrested in its movement toward h, then will the point F³ (which had been moving toward f) become for that interval of time a fixed point, and the still 75 continued movement of the arm D toward d will move the lever F by its connecting-link D², and thus cause the steam-valve E to close over the port a, and the valve E' to close over the port a³, by which the movement of the arm 80 D toward d is arrested, and the position of the arm D at d will be maintained so long as the lever H occupies its position at h. By a parity of motions, when the lever H is moved toward h' and arrested at that point, then will the arm D be arrested at d', the movement of the valves E and E' through the rod E² and lever F having operated in the reverse direction to that described, and opened and closed the ports a' and a³ of the respective cylinders A and A'. 90

The office of the cylinder A', with its contents or the equivalent therefor, is to provide a suitable frictional resistance to the movement of the piston-rod C', so that the movement of said rod may be adjusted to such speed or velocity 95 as may be most advantageous to the operation of the machine.

If, from leakage or any other cause, the movement of pistons B B', rods C C', and arm D should continue after the lever H had been 100 thrown into position, then will the continued movement of arm D, through the link D² and

fulcrum F^3 of rod G , reverse the movement of lever F , rod E^2 , and valves E E' , and thus, admitting steam to the opposite side of piston B , will arrest the further movement of the arm D .

Having described my invention and its mode of operation, I desire to secure by Letters Patent the following claims.

1. In a steam or automatic reversing device, the lever F , in combination with the valve E of the cylinder A , valve-rod E^2 , link D^2 , and arm D , as shown, and for the purpose specified.

2. The lever F , connected as shown, whereby the joints F' , F^2 , and F^3 automatically become the fulcrum-points of movement, in combination with the valves E E' , cylinders A A' ,

pistons B B' , piston-rods C C' , arm D , link D^2 , lever H , or its equivalent, rod or link G , and valve-rod E^2 , substantially as shown, and for the purpose specified.

3. In a steam or automatic reversing device, the automatic opening and closing of the valves E E' over their respective ports by the movement of piston B and arm D , in combination with lever F , link D^2 , and rod E^2 , substantially as shown, and for the purpose set forth.

WILLIAM E. GOOD.
